9 Claims. (Cl. 260—668)

1

This invention relates to a process for the production of commercial grades of toluene suitable for nitration, etc., in a more economical manner from naphthenic petroleum distillates.

Toluene is one of the primary compounds upon which aromatic chemistry is based. It is employed in large quantities as a starting material for the synthesis of a great variety of useful products such as dyestuffs, explosives, drugs, flavors, perfumes, photographic developers, plastics, intermediate chemicals, and many others. The primary source of toluene has been the distillation of coal. Consequently, the supply of toluene has been primarily dependent upon the condition of the steel and coal-tar industries and has been thus limited. Aside from the numerous uses where its application is more or less obligatory, toluene has a great many potential uses which have been curtailed by its limited supply and relatively high price. As a consequence, considerable attention has been given to the possibility of producing toluene from other sources.

Certain processes have been perfected whereby toluene may be produced from petroleum fractions. One of these is to recover toluene from aromatic petroleum fractions, particularly cracked distillates. Certain petroleums and most highly cracked distillates contain appreciable quantities of aromatic hydrocarbons which may be recovered in the form of aromatic fractions and even relatively pure aromatic hydrocarbons by a suitable combination of steps involving fractionation, extraction, etc. The recovery of toluene from such distillates is, however, quite expensive. Only a small proportion of these distillates is toluene and, consequently, large quantities of material must be processed in order to recover relatively small yields.

More recently, methods for the production of toluene from naphthenic distillates by catalytic dehydrogenation processes have been perfected. Thus, in one such process a naphthenic petroleum is fractionated to separate a fraction boiling between about 205° F. and 230° F. and the fraction is treated under dehydrogenation conditions with a dehydrogenation catalyst. This fraction contains, besides the naturally existing toluol, toluol produced from the methyl cyclohexane which is present in appreciable quantities in such distillates. The toluol is recovered from the dehydrogenated product by a combination of extraction and fractionation steps. In this process the yields of toluene include considerable quantities of toluene produced from the methyl cyclohexane by dehydrogenation.

In an improved modification of this process a fraction boiling between about 190° F. and 230° F. is separated and subjected to a catalytic isomerization treatment prior to the dehydrogenation treatment. This improved modification allows

2

the catalyst to be used more efficiently and produces increased yields of toluene from dimethyl cyclopentanes found in considerable concentrations in the naphthenic distillates.

5 In a further improved modification of the process a fraction boiling between about 190° F. and 230° F. is separated and then divided into two fractions boiling above and below about 205° F. The lower boiling fraction is subjected to a selective isomerization treatment and then the two fractions are recombined and subjected to a catalytic dehydrogenation treatment.

The object of the present invention is to provide a further improved process of the described 15 type whereby commercial grades of toluene suitable for nitration may be produced from naphthenic petroleum distillates in a more economical manner. A more particular object of the invention is to provide a process wherein substantially

20 all of the more easily convertible hydrocarbons are converted to toluene while at the same time avoiding excessive processing costs. Another more particular object of the invention is to provide a process whereby excellent yields of toluene

25 may be produced with a minimum consumption of catalyst, especially in the catalytic isomerization step. Still another object is to provide a process wherein the dehydrogenation may be effected with a high ratio of on-stream time to

30 regeneration time per process cycle and wherein the catalyst may be most effectively maintained at a suitable activity for extended periods of time before it is necessary to replace it. A still further object is to provide a process wherein by recycling 35 certain of the products the efficiency and economy of the total operation are considerably increased. Various advantages of the process, the realization of which constitute further objects of the invention, will be seen in the following more detailed 40 description of the process and certain of its modifications.

The process of the invention is designed and applicable for the production of toluol from naphthenic petroleum fractions. By naphthenic petroleum fractions is meant petroleum fractions of natural or synthetic origin containing an appreciable quantity of naphthenic hydrocarbons and paraffinic hydrocarbons having seven carbon atoms. Suitable naphthenic petroleum fractions

50 are obtained from a large number of western and midwestern crude petroleums. A few typical sources are, for example, Los Angeles Basin crude, Huntington Beach crude, Dominguez Hill crude, Ventura crude, Ten Section crude and Kettleman

55 Hills crude. The naphthenic petroleum fractions are usually in the nature of straight run gasoline fractions and are substantially free of detrimental impurities. The process, however, provides for the treatment in conjunction with such substantially saturated materials of unsaturated

naphthenic fractions as cracked stocks, reformed stocks and the like.

In one specific embodiment the process of the present invention comprises fractionating a substantially saturated naphthenic distillate into a lower boiling fraction II boiling below about 180° F.-190° F. and a higher boiling fraction III boiling above about 180° F.-190° F.; subjecting said higher boiling fraction III to a fractional distillation to separate a lower boiling fraction IV boiling below about 200° F.-212° F. and a higher boiling fraction V boiling above about 200° F.-212° F.; subjecting said lower boiling fraction IV to a catalytic isomerization treatment to produce an isomerate VI; subjecting the isomerate VI to a fractional distillation to separate a lower boiling fraction VII boiling below about 200° F.-212° F. and a higher boiling fraction VIII boiling above about 200° F.-212° F.; recycling a portion of said lower boiling fraction VII to the isomerization treatment with the lower boiling fraction IV; subjecting said higher boiling fraction VIII in admixture with the above-said higher boiling fraction V to a fractional distillation to separate a lower boiling fraction IX boiling below about 218° F.-235° F. and a higher boiling fraction X boiling above about 218° F.-235° F.; subjecting said lower boiling fraction IX per se or in admixture with a similar fraction of an unsaturated naphthenic distillate to a catalytic dehydrogenation treatment to produce a reformate XI; subjecting said reformate XI in admixture with recycle bottoms XII to a fractional distillation to separate a lower boiling fraction XIII boiling below about 233° F.-266° F. and a higher boiling fraction XIV boiling above about 230° F.-266° F.; separating said lower boiling fraction XIII into an aromatic fraction and a non-aromatic fraction XVI by means of a selective solvent; recovering an aromatic fraction XVII from said selective solvent; subjecting said aromatic fraction XVII to a sulfuric acid refining treatment and then fractionally distilling the same to recover a lower boiling fraction consisting of substantially pure toluene and a higher boiling fraction consisting of said recycle bottoms XII.

The invention also comprises modifications and more specific embodiments of the above-outlined process which are advantageously but not necessarily employed. Thus, in one such modification the fractionation of said higher boiling fraction II is effected in the presence of recycled isomerate VI; in another modification the recycle of said lower boiling fraction VII is reduced or eliminated and said lower boiling fraction VII is preferably subjected to further processing. These and various other preferred embodiments of the invention are described in connection with the following more detailed description of the process.

The outline of the process given in the preceding paragraph is amplified in the following description wherein various important features of the process are described in connection with a typical operation comprised within the scope of the invention. To assist in the description, reference is had to the attached drawing forming a part of the specification, wherein there is shown by means of diagrammatic figures one assembly of apparatus in which the process of the invention may be advantageously carried out.

In order to illustrate the various details of the process in a clear and comprehensive manner without unnecessary crowding, the assembly of

apparatus is divided into three sections designated Figures I, IA and IB, respectively. Referring to the drawing, Figure I, a naphthenic distillate, such as a straight run naphthenic gasoline, enters the system via line 1 and is pumped via pump 2 to a fractionating column 3. The fractionating column 3 is provided with the usual condenser 4, surge tank 5, recycle reflux pump 6, recycle reflux line 7, and reboiler 8. A fractionating column with these accessories constitutes a fractionating apparatus and will be simply so designated hereinafter. The conditions in the fractionating apparatus are so adjusted as to remove as an overhead product substantially all of the original distillate boiling below 180° F.-190° F. This lower boiling overhead fraction I is withdrawn from the system via line 9. The bottom product from the fractionating apparatus is passed via pump 11 and line 12 to a second fractionating apparatus 13, wherein it is fractionated in admixture with recycle distillate entering via line 14. The conditions in fractionating apparatus 13 are so adjusted as to remove as an overhead product substantially all of the material boiling below 200° F.-212° F. The bottom product from fractionating apparatus 13 is passed via line 15 and pump 16 (Figure IA) to a fractionating apparatus 17, wherein it is fractionated in conjunction with the bottom product from fractionating apparatus 18, as will be more fully described below. Returning to Figure I, the overhead product from fractionating apparatus 13 passes via line 19 to one or more isomerization reactors 21 and/or 22, wherein it is contacted under isomerization conditions with one of the known isomerization catalysts. The isomerization is effected in the vapor or liquid phase, preferably in the liquid phase in the presence of a promoter and, if desired, hydrogen. Preferred catalysts are those comprising aluminum chloride and/or aluminum bromide. Of these, aluminum chloride is preferred since it is the least expensive, easier to employ and has much less tendency than aluminum bromide to cause degradation reactions. Other acid-acting catalysts of the Friedel-Crafts type such as the chlorides of Zr, Zn, Sn, Be, Nb, Ta, Sb, B and Cd may also be employed, if desired, in conjunction with the aluminum chloride. A preferred isomerization catalyst, which has been found to be particularly suitable for the present process, is a slurry of aluminum chloride in a liquid aluminum chloride complex. Aluminum chloride (aluminum bromide may also be used) is charged to a suitable reactor 23 and reacted therein with a suitable complex-forming material added via line 24 and pump 25, preferably in the presence of hydrogen chloride added via line 26. Any of a number of known complexes may be formed. Very suitable materials with which to form the complex are, for example, smokeless kerosene, kerosene extract, cyclohexene, and aromatic hydrocarbons. The aluminum chloride is preferably added in excess, or additional aluminum chloride may be added after the desired complex is formed. The excess may, however, be very small. The complex catalyst is withdrawn from the reactor 23, forced via pump 27 through lines 28, 29, 31, 32, 33, 34 and 35 to reactors 21 and 22 as required. Reactors 21 and 22 are preferably equipped with heating and mixing means (not shown) but may be of conventional design. The mixture of hydrocarbons and fluid catalyst passes from the reactors to suitable separators 30 and 36, wherein the mixture is allowed to stratify. The heavier

catalyst layer is recycled via lines 32, 33, 34 and 35. Spent or partially spent catalyst may be removed intermittently or continuously via lines 37 and 38. The isomerization treatment is preferably effected in the presence of one of the known promoters, such as an alkyl halide, boron fluoride or more particularly hydrogen chloride. The promoter, preferably hydrogen chloride, is added to the system via lines 39, 41 and 42. The upper layer from separators 30 and 36, consisting of hydrocarbons and promoter, passes via line 43 to a separator 44. Hydrogen chloride is withdrawn from separator 44 via lines 45 and 46 and compressed via compressor 47 into a surge tank 48, wherein small amounts of liquefied materials are separated and intermittently withdrawn via line 49 and mixed with stock in line 51. In order to avoid excessive dilution of the hydrogen chloride with use, a small amount of the recycled gas may be withdrawn intermittently or continuously via line 52. The bulk of the hydrogen chloride is, however, advantageously recycled back to the reactors via lines 52, 41 and 42.

The conditions in the isomerization reactors 21 and 22 are adjusted to afford a relatively rapid clean-cut isomerization with little or no formation of fixed gases. The preferred conditions will depend upon the degree of mixing, the catalyst activity and the concentration of hydrogen chloride employed. Suitable preferred conditions, using an aluminum chloride-kerosene extract complex catalyst, are, for example, as follows:

Contact time _____ min. 5 to 45
 Temperature _____ °F. 50 to 212
 Pressure _____ atm. 1 to 20
 Concentration of HCl (based on the hydrocarbon) per cent by weight 0.1 to 5

Instead of employing the isomerization reactors in parallel as shown, they may, if desired, be connected in series in the conventional manner with countercurrent flow of the catalyst. The product from the isomerization reactor or reactors, after separation of the bulk of the hydrogen chloride in separator 44 is pumped via pump 53, line 54 and cooler 55 to a caustic scrubbing system to remove dissolved hydrogen chloride. Thus, the cooled product is mixed with caustic solution in a jet mixer 56 and passed to a separator 57. Caustic solution is recycled via lines 58, 59, pump 61 and line 62. The caustic scrubbed liquid hydrocarbon fraction is then passed via line 63 to a surge tank 64 (Figure IA) and then via lines 65 and 66 to fractionating apparatus 18. A portion of the product may also advantageously be passed via lines 14 and 12 back to fractionating apparatus 13. In this way the relative efficiencies of the fractionations in fractionating apparatus 13 and 18 may be controlled. The conditions in fractionating apparatus 18 (Figure II) are so adjusted as to remove as an overhead product substantially all of the material boiling below 200° F.-212° F. This overhead fraction may be handled in either one of two ways. According to one embodiment, this fraction is advantageously separated into two portions, one of which is passed via line 51 to the overhead product from fractionating column 13 (Figure I) and the other of which is withdrawn from the system via lines 51 and 67. The relative amounts of the two portions will depend upon the particular circumstances. In general, however, the portion withdrawn will range between about one-fourth and two-thirds of the total fraction.

According to the other embodiment, the total

overhead product from fractionating apparatus 18 may be passed via lines 51, 68 and 69 (Figure I) to an isomerization reactor 71, wherein it is treated as described above. Catalyst enters reactor 71 via line 28 and hydrogen chloride enters the reactor via line 72. The mixture of catalyst and hydrocarbon is separated and then the hydrocarbon and hydrogen chloride are separated as described above. The hydrogen chloride passes via line 73 to separator 44. The hydrocarbon phase is passed via line 75 to a caustic scrubbing system 76 (Figure IA) as previously described. The caustic washed product is passed via line 77 and surge tank 78 to a fractionating apparatus 79. The conditions in fractionating apparatus 79 are adjusted so as to remove as an overhead product substantially all of the material boiling below 205° F.-210° F. This overhead fraction is withdrawn from the system via line 81. The bottom fraction from fractionating apparatus 79 is passed via pump 82 and line 83 to line 84 where it is mixed with the bottom product from fractionating apparatus 18.

The bottom fraction from fractionating apparatus 18, alone or in admixture with the bottom fraction from fractionating apparatus 79, is passed via line 84 and heat exchanger 85 to fractionating apparatus 17, wherein it is fractionated in conjunction with the bottom product from fractionating apparatus 13, entering via line 15 and pump 16, as previously described, and also advantageously in conjunction with extract and the bottoms from fractionating apparatus 141 entering via line 86, as will be described below. The conditions in fractionating apparatus 17 are adjusted so as to remove as an overhead product substantially all material boiling up to 218° F.-235° F. The bottom product from fractionating apparatus 17 is withdrawn from the system via pump 87 and line 88. A portion of this bottom product is preferably withdrawn via line 89 to serve as a scrubbing medium, as will be described below.

The overhead product from fractionating apparatus 17 is advantageously mixed with an olefinic hydrocarbon fraction such, for instance, as an unsaturated cracked or reformed gasoline fraction. The addition of the olefinic fraction considerably simplifies the problem of supplying the endothermic heat of the subsequent dehydrogenation reaction; also, the catalytic dehydrogenation efficiency may be appreciably increased. In the subsequent dehydrogenation treatment any methyl cyclohexane which may be present in the added unsaturated fraction is converted into toluene. It is therefore advantageous to employ a naphthenic olefin fraction from a cracked, reformed, polyformed or similar product including the methyl cyclohexane usually present in appreciable concentrations in such distillates. Also, such unsaturated fractions usually contain appreciable concentrations of toluene and this may be most advantageously recovered by the present method since the interfering unsaturated hydrocarbons are substantially saturated in the subsequent treatment prior to the recovery step. It is therefore advantageous to employ unsaturated fractions embracing the boiling range of about 225° F.-235° F. Advantageously employed unsaturated fractions are, for example, fractions of aromatic- and naphthene-containing unsaturated fractions boiling largely below about 235° F. and above about 205° F. The unsaturated fraction may be added in any amount but is preferably not added in such quantities that there is

an appreciable hydrogen consumption in the subsequent catalytic treatment. The olefinic material may be added via line 80.

The overhead product from fractionating apparatus 17, per se or in admixture with the above-described unsaturated fraction, is passed via line 91 through a suitable heating coil 92 in heater 93, wherein it is vaporized and raised to a suitable reaction temperature for the dehydrogenation treatment. The vaporized hydrocarbon feed, leaving heater 93 via line 94, is mixed with hot hydrogen, entering via line 95, and the mixture is subjected to a suitable dehydrogenation treatment. The dehydrogenation treatment may be effected with any of the many catalysts known to be suitable for the dehydrogenation of naphthenic hydrocarbons and may be effected in various apparatus, such as conventionally used in catalytic reforming, catalytic hydroforming, and catalytic dehydrogenation. Particularly suitable catalysts comprise the compounds, preferably the oxides, of the metals selected from the left-hand members of groups IV, V and VI of the periodic system of the elements, if desired, in conjunction with promoting amounts of compounds, preferably the oxides, of metals selected from the group I and/or group VIII of said system. Very suitable catalysts comprise, for example, the oxides of Cr, Mo, Ti and/or V supported upon a major amount of an adsorptive carrier such as an adsorptive alumina. The dehydrogenation conditions employed will depend somewhat upon the particular catalyst. One suitable assembly of apparatus applicable with most dehydrogenation catalysts is illustrated in the attached drawing in Figure IA. The dehydrogenation system comprises two banks of catalytic converters manifolded in such a way that while one bank is processing, the other bank may be regenerated. The converters in each bank may be connected in parallel or in series as shown. If it is assumed that the upper bank of converters 96, 97 and 98 is processing while the lower bank of converters 99, 101 and 102 is undergoing regeneration, the mixture of hydrocarbon feed and hydrogen, leaving heater 93 via line 94, is passed via manifold line 103 to converter 96. After passing through converter 96, the partially converted mixture is passed through heat exchanger 104, converter 97, heat exchanger 105, converter 98, manifold line 106, and heat exchanger 107 to a separator 108. At the same time inert gas is circulated by means of compressor 109 through lines 111, 112, and 113 into manifold line 103 and thence through reactor 99, heat exchanger 114, reactor 101, heat exchanger 115, reactor 102, and line 116. The inert gas recirculation system illustrated is that described in U. S. Patent 2,262,427. Air is pumped via pump 117 to lines 118 and 119 from the latter of which it is fed in controlled quantities into the recirculated inert gas stream.

The gaseous products in separator 108 are withdrawn via line 121 and divided into two portions. One portion is passed via line 122 to a cooler 123 and low pressure separator 124 (Figure IB) and is treated as hereinafter more fully described. The other portion is compressed by compressor 125 (Figure IA) into a tower 126 and is then recycled back to the heater 93 via line 127.

It is found, however, that in the present process utilizing the particular fractionation, recycle and isomerization steps described above, it is most advantageous to employ a selective catalyst of the metal sulfide type such, in particular, as a mixture of tungsten sulfide and a sulfide of a

metal of the iron group. A specific catalyst of this preferred type is tungsten sulfide-nickel sulfide, having a mole ratio of nickel to tungsten of from about 1:1 to 2:1. The dehydrogenation conditions employed will vary somewhat depending upon the particular catalyst employed. When employing the preferred tungsten sulfide-nickel sulfide catalyst (hereinafter referred to as W-Ni sulfide catalyst) suitable preferred conditions are as follows:

Temperature ..... ° F. 750 to 1000
Pressure ..... atm. 5 to 75
Mole ratio of hydrogen to hydrocarbon feed. 4:12
Liquid hourly space velocity ..... 0.5 to 4.0

When employing the preferred W-Ni sulfide catalyst, the regeneration is preferably effected with SO_2 rather than air. For this purpose hydrogen sulfide from any source is introduced via line 128, pump 129 and line 131 to an SO_2 generator 132, wherein it is burned with air introduced via pump 133 and line 134. The combustion products containing SO_2 , preferably after being dried by means not shown, pass via manifolding pipe 19 to the various converters undergoing regeneration. Periodically, the catalyst may be remade and sulfided in the reactors by simply passing unburnt hydrogen sulfide through the system. The regeneration of the catalyst with SO_2 is described in more detail in copending application Serial No. 434,893. The hydrogen sulfide used for preparing the SO_2 may be obtained in part from the recycled hydrogen gas. Thus, the tower 126 may advantageously be the scrubbing tower of a Shell Phosphate Unit. Phosphate solution enters the tower via lines 135 and 136, and is withdrawn via line 137 to a stripper 138 in the known manner. Hydrogen sulfide is recovered via line 131 and passed to the SO_2 generator 132 or drawn to storage via line 128.

The liquid product from separator 108 (Figure IA) is passed via line 139 to a low pressure separator 141 (Figure IB) wherein further quantities of gases are separated. These separated vapors are further cooled in cooler 142 and are finally passed to a third separator 143, wherein small quantities of condensable liquids are collected. The liquid product from the low pressure separator 141 is passed via pump 144 and lines 145 and 146 to fractionating apparatus 147, wherein they are fractionated in conjunction with the bottom product from fractionating apparatus 148, described below. The conditions in fractionating apparatus 147 are adjusted so as to remove as an overhead product all or most of the toluene while retaining substantially all of the higher boiling products in the bottom fraction withdrawn via line 149. The economy of the fractionation steps may usually be considerably improved if this bottom product is recycled back to fractionating apparatus 17. For this purpose line 149 is shown connecting with line 186 which leads to fractionating apparatus 17.

The overhead product from fractionating apparatus 147 is mixed with the liquid products from the separators 124 and 143 and the mixture subjected to a suitable treatment to recover toluene. A preferred method is by extractive distillation in the known manner. Thus, the mixture is passed via line 151 to an extractive distillation column 152, wherein it is distilled in conjunction with a higher boiling polar solvent, entering via line 153. Non-aromatic impurities are removed overhead via line 154. The extract phase is removed via line 155 and passed to a stripping col-

umn 156, wherein the toluene is separated from the solvent. The solvent is recycled back to the extractive distillation column 152 via line 153. The toluene is removed as an overhead product from column 156 via line 157. This material consisting essentially of toluene but containing small amounts of impurities is treated with sulfuric acid in tank 158 (and, if desired, caustic-washed in means not shown). The treated product is withdrawn to a settling tank 159 and is then passed via line 161 to a final fractionating apparatus 148. In fractionating apparatus 148 the conditions are adjusted to recover as an overhead product substantially pure toluene, containing substantially no higher boiling product. This product is removed from the system via line 162. The bottom product from fractionating apparatus 148 contains toluene contaminated with higher boiling products. This fraction is advantageously passed via line 146 back to fractionating column 147.

The above-described combination of steps effected in apparatus 147, 152, 156 and 148 constitutes a particularly advantageous, preferred embodiment of the invention. By employing the described recycle the maximum purity of the toluene may be maintained with a minimum of fractionation costs. Another advantageous preferred embodiment of the process affording maximum yields with low recovery costs lies in the described method of separating the normally liquid products from the gases in the product from the dehydrogenation reactors. According to a preferred embodiment, the gaseous fraction separated in separator 124 (Figure 1B) is passed to a column 163, wherein it is scrubbed with a portion of the bottom product from fractionating apparatus 17 (Figure 1A). The scrubbing liquid is then passed via line 86 to fractionating apparatus 17, wherein it is fractionated in conjunction with the bottom product from fractionating apparatus 13. Another important feature of the described process is the described recycle of a portion of the overhead product from fractionating apparatus 18 to the overhead product from fractionating apparatus 13 in combination with the passage of the bottom product from the fractionating apparatus 13 to the fractionating apparatus 17. Another important feature of the process is the addition of an olefinic fraction, preferably containing methyl cyclohexane and/or toluene, to the overhead product from fractionating apparatus 17. By the described combination of recycles in conjunction with the described preferred dehydrogenation treatment substantially all of the more easily converted components of the feed are converted to toluene with a minimum cost of separation.

The process of the invention as described above, it will be seen, comprises a plurality of unit operations, which in themselves are known, combined with specific fractionations and novel recycles in such a manner as to afford a novel process which, when applied to the particular type of petroleum distillates described, afford a more advantageous and economical production of substantially pure toluene. In so far as the known unit operations such as fractionation, isomerization, dehydrogenation, catalyst regeneration, extraction of toluene from aromatic distillates, and the like are concerned, these may be operated in any of the known suitable manners with the various known expedients and apparatus and are not limited to the specific embodiments illustrated and described. In a few cases, however, certain

embodiments of these known unit processes have been found to be most advantageous when employed in the present combination of steps, and these are more particularly pointed out above and in certain of the more specific claimed embodiments.

What is claimed is:

1. A process for the production of commercial grades of toluene suitable for nitration from naphthenic petroleum distillates which comprises the combination of steps of fractionating a substantially saturated naphthenic petroleum distillate I into a lower boiling fraction II boiling below about 180° F.-190° F. and a higher boiling fraction III boiling above about 180° F.-190° F., subjecting said higher boiling fraction to a fractional distillation to separate a lower boiling fraction IV boiling below about 200° F.-212° F. and a higher boiling fraction V boiling above about 200° F.-212° F., subjecting said lower boiling fraction IV to a catalytic isomerization treatment under isomerization conditions with an aluminum chloride isomerization catalyst to produce an isomerizate VI, subjecting isomerizate VI to a fractional distillation to separate a lower boiling fraction VII boiling below about 200° F.-212° F. and a higher boiling fraction VIII boiling above about 200° F.-212° F., subjecting said higher boiling fraction VIII in admixture with the above-said higher boiling fraction V and in admixture with a recycled bottom fraction XIV specified below and in admixture with a recycled fraction X specified below to a fractional distillation to separate a lower boiling fraction IX boiling below about 218° F.-235° F. and a higher boiling fraction X boiling above about 218° F.-235° F., subjecting said lower boiling fraction IX to a catalytic dehydrogenation treatment to produce an aromatic fraction XI, separating from the aromatic fraction XI fixed gases including hydrogen, scrubbing at least a portion of said fixed gases including hydrogen with a portion of said higher boiling fraction X and subjecting the higher boiling fraction X used in said scrubbing to the above-said fractionation in conjunction with said higher boiling fractions VIII, V and XIV, subjecting the aromatic fraction XI to a fractional distillation in admixture with recycled bottoms XII specified below to separate a lower boiling fraction XIII boiling below about 233° F.-266° F. and said higher boiling recycled bottom fraction XIV boiling above about 230° F.-266° F., separating said lower boiling fraction XIII into an aromatic fraction XV and a non-aromatic fraction XVI, subjecting said aromatic fraction XV to a sulfuric acid refining treatment and then fractionally distilling the same to recover a lower boiling fraction XVII consisting of substantially pure toluene and a higher boiling fraction consisting of said recycle bottom fraction XII.

2. Process according to claim 1 in which the dehydrogenation is effected in the presence of recycled hydrogen with a tungsten sulfide-nickel sulfide catalyst under the following conditions:

Temperature..... ° F. 750 to 1000
 Pressure..... atmospheres 5 to 75
 Mol ratio of hydrogen to hydrocarbon feed..... 4:1 to 12:1
 Liquid hourly space velocity..... 0.5 to 4

3. In a process for the production of commercial grades of toluene suitable for nitration from naphthenic petroleum distillates which comprises separating from a naphthenic petroleum distillate a fraction comprising alkyl-pentamethylene

hydrocarbons, isomerizing said alkyl pentamethylene hydrocarbons to methyl cyclohexane, dehydrogenating the methyl cyclohexane so produced to toluene and recovering substantially pure toluene from the dehydrogenated product, the improvement which comprises the combination of steps of separating from a naphthenic petroleum distillate a fraction III boiling above about 180° F.-190° F., subjecting said fraction III to a fractional distillation to separate a lower boiling fraction IV boiling below about 200° F.-212° F. and a higher boiling fraction V boiling above about 200° F.-212° F., subjecting said lower boiling fraction IV to a catalytic isomerization treatment under isomerization conditions with an aluminum chloride isomerization catalyst to produce an isomerizate VI, subjecting the isomerizate VI to a fractional distillation to separate a lower boiling fraction VII boiling below about 200° F.-212° F. and a higher boiling fraction VIII boiling above about 200° F.-212° F., and subjecting said higher boiling fraction VIII in conjunction with said higher boiling fraction V to a fractional distillation to separate a lower boiling fraction IX boiling below about 218° F.-235° F. and a higher boiling fraction X boiling above about 218° F.-235° F.

4. Process according to claim 3 in which the isomerization treatment is effected with a slurry of aluminum chloride in an aluminum chloride complex under the following conditions:

Hydrocarbon-catalyst phase ratio... 1:1 to 10:1
 Contact time..... minutes 5 to 45
 Temperature..... ° F. 50 to 212
 Pressure..... atmospheres 1 to 10
 Concentration of HCl based on the
 feed..... % by weight 0.1 to 5

5. In a process for the production of commercial grades of toluene suitable for nitration from naphthenic petroleum distillates which comprises separating from a naphthenic petroleum distillate a fraction comprising alkyl pentamethylene hydrocarbons, isomerizing said alkyl pentamethylene hydrocarbons to methyl cyclohexane, dehydrogenating the methyl cyclohexane so produced to toluene and recovering substantially pure toluene from the dehydrogenated product, the improvement which comprises the combination of steps of separating from a naphthenic petroleum distillate a fraction III boiling above about 180° F.-190° F., subjecting said fraction III to a fractional distillation to separate a lower boiling fraction IV boiling below about 200° F.-212° F. and a higher boiling fraction V boiling above about 200° F.-212° F., subjecting said lower boiling fraction IV in conjunction with a portion of fraction VII specified below to a catalytic isomerization treatment under isomerization conditions with an aluminum chloride isomerization catalyst to produce an isomerizate VI, subjecting the isomerizate VI to a fractional distillation to separate a lower boiling fraction VII boiling below about 200° F.-212° F. and a higher boiling fraction VIII boiling above about 200° F.-212° F., recycling at least a portion of said lower boiling fraction VII to the isomerization treatment with the lower boiling fraction IV and subjecting said higher boiling fraction VIII in conjunction with said higher boiling fraction V to a fractional distillation to separate a lower boiling fraction IX boiling below about 218° F.-235° F. and a higher boiling fraction X boiling above about 218° F.-235° F.

6. In a process for the production of commer-

cial grades of toluene suitable for nitration from naphthenic petroleum distillates which comprises separating from a naphthenic petroleum distillate a fraction comprising alkyl pentamethylene hydrocarbons, isomerizing said alkyl pentamethylene hydrocarbons to methyl cyclohexane, dehydrogenating the methyl cyclohexane so produced to toluene and recovering substantially pure toluene from the dehydrogenated product, 5 the improvement which comprises the combination of steps of separating from a naphthenic petroleum distillate a fraction III boiling above about 180° F.-190° F., subjecting said fraction III in admixture with recycled isomerizate VI mentioned below to a fractional distillation to separate a lower boiling fraction IV boiling below about 200° F.-212° F. and a higher boiling fraction V boiling above about 200° F.-212° F., subjecting said lower boiling fraction IV to a 10 catalytic isomerization treatment under isomerization conditions with an aluminum chloride isomerization catalyst to produce an isomerizate VI, combining a portion of said isomerizate VI with said fraction III, subjecting the remainder of said isomerizate VI to a fractional distillation to separate a lower boiling fraction VII boiling below about 200° F.-212° F. and a higher boiling fraction VIII boiling above about 200° F.-212° F., and subjecting said higher boiling fraction VIII 15 in conjunction with said higher boiling fraction V to a fractional distillation to separate a lower boiling fraction IX boiling below about 218° F.-235° F. and a higher boiling fraction X boiling above about 218° F.-235° F.

35 7. In a process for the production of commercial grades of toluene suitable for nitration from naphthenic petroleum distillates which comprise separating from a naphthenic petroleum distillate a fraction comprising alkyl pentamethylene hydrocarbons, isomerizing said alkyl pentamethylene hydrocarbons to methyl cyclohexane, dehydrogenating the methyl cyclohexane so produced to toluene and recovering substantially pure toluene from the dehydrogenated product, 40 the improvement which comprises the combination of steps of fractionating the isomerized feed prior to the dehydrogenation treatment into a lower boiling fraction IX boiling below about 218° F.-235° F. and a higher boiling fraction X boiling above about 218° F.-235° F., subjecting said lower boiling fraction IX to a catalytic dehydrogenation treatment to produce an aromatic fraction XI, separating from the aromatic fraction XI fixed gases including hydrogen, scrubbing at least a portion of said fixed gases including hydrogen with a portion of said higher boiling fraction X, and subjecting the higher boiling fraction X used in said scrubbing to the above-said fractionation to produce said fractions IX and X.

55 8. In a process for the production of commercial grades of toluene suitable for nitration from naphthenic petroleum distillates which comprises separating from a naphthenic petroleum distillate a fraction comprising alkyl pentamethylene hydrocarbons, isomerizing said alkyl pentamethylene hydrocarbons to methyl cyclohexane, dehydrogenating the methyl cyclohexane so produced to toluene and recovering substantially pure toluene from the dehydrogenated product, 60 the improvement which comprises the combination of steps of fractionating the isomerized product prior to the dehydrogenation treatment in conjunction with a higher boiling fraction XIV specified below into a lower boiling fraction

70 75

IX boiling below about 218° F.-235° F. and a higher boiling fraction X boiling above about 218° F.-235° F., subjecting said lower boiling fraction IX to a catalytic dehydrogenation treatment to produce an aromatic fraction XI, subjecting the aromatic fraction XI to a fractional distillation to separate a lower boiling fraction XIII boiling below about 233° F.-266° F. and said higher boiling fraction XIV boiling above about 230° F.-266° F.

9. In a process for the production of commercial grades of toluene suitable for nitration from naphthenic petroleum distillates which comprises separating from a naphthenic petroleum distillate a fraction comprising alkyl pentamethylene hydrocarbons, isomerizing said alkyl pentamethylene hydrocarbons to methyl cyclohexane, dehydrogenating the methyl cyclohexane so produced to toluene and recovering substantially pure toluene from the dehydrogenation product, the improvement which comprises the combination of steps of subjecting the aromatic fraction XI produced by the dehydrogenation treatment to a fractional distillation in admixture with a recycled bottom fraction XII specified below to separate a lower boiling fraction

XIII boiling below about 233° F.-266° F. and a higher boiling fraction XIV boiling above about 230° F.-266° F., separating said lower boiling fraction XIII into an aromatic fraction XV and a non-aromatic fraction XVI, subjecting said aromatic fraction XV to a sulfuric acid refining treatment and then fractionally distilling the same to recover a lower boiling fraction XVII consisting of substantially pure toluene and a higher boiling fraction consisting of said recycled bottom fraction XII.
